CYLINDER LINER FOR OPPOSED PISTON ENGINES

Hans Steiner, Winterthur, Switzerland, assignor
to Sulzer Freres, Societe Anonyme, Winterthur,
Switzerland

Application August 9, 1945, Serial No. 609,858
In Switzerland September 26, 1944

8 Claims. (Cl. 123—173)

1

It is known to cool the middle part of the cylinder liner of opposed-piston internal combustion engines by means of cooling passages bored obliquely to the cylinder axis. This solution has the disadvantage that the strength of the wall which lies between the cooling passages and the surface heated by the gases is lowest in the middle sectional plane of the cylinder and increases to both sides. The most intensive cooling effect, however, is desirable in the zone in which the piston rings are situated when the pistons are in their inner dead centre.

This disadvantage is removed by the present invention by arranging the passages in such a way that their distance from the cylinder axis is at a minimum outside the middle plane of the cylinder, and in particular in the zone in which the piston rings are situated when the pistons are in their inner dead centre. The end is thus attained that the part of the cylinder liner over which the piston rings pass remains cool, a fact which has a favourable influence on the working of the engine and its consumption of lubricating oil and which greatly reduces the heat stresses occurring in the liner.

A number of embodiments of the invention are shown in the accompanying drawings, in which

Fig. 1 is a longitudinal section through the cylinder liner of an opposed-piston engine, designed according to the invention;

Fig. 2 shows the middle part of the liner from Fig. 1 to a larger scale;

Fig. 3 shows another design of the middle part of the cylinder liner;

Fig. 4 is the cross-section along the line IV—IV of Fig. 2; and

Fig. 5 shows in cross-sectional elevation a further form of cylinder liner.

In Fig. 1 the cylinder liner 1 is formed in one piece. The two pistons 2 and 3 are shown in the outer dead centre. The inner dead centre of the pistons 2 and 3 is indicated by chain-dotted lines. The scavenging and supercharging air enters through the scavenging port 4; the combustion gases issue through the exhaust port 5. For cooling the strengthened middle part 6, cooling medium is introduced into the cooling jacket 31 through the inlet branch 32. The cooling medium flows through passages 8 arranged in the strengthened middle part obliquely to the cylinder axis entering these passages at 29 and leaving at 30. It then passes out of the cooling jacket 31 through the outlet branch 33.

In the arrangement according to the invention the strengthened middle part 6 is bored from

2

entrance orifices 29 and exit orifices 30 on its inlet and outlet sides respectively in such a way that the axes of the passages originating on each side belong to the generating lines of a single-sided hyperboloid of rotation whose axis of rotation *a* coincides with the cylinder axis. Each pair of such passages 8, 9 intersects in the middle plane of the cylinder, so that a continuous channel is formed for the cooling medium. The valves (for example fuel and starting valves) are designated by the numeral 10.

Fig. 2 shows the strengthened middle part 6 to a larger scale. The sectional plane of the drawing cuts the ellipses 12, 13, 14, 15, 16, 17, 18, 19 out of the single cooling passages. The broken line *a*—*a* defines the surface containing the axes of all the passages.

The pistons 2, 3 are shown in the inner dead centre. Near the middle plane IV—IV of the cylinder, and thus in a zone which is never passed over by the piston rings, the distance of the cooling passages from the cylinder axis increases.

Fig. 4 shows a cross-section through the middle plane of the cylinder along the line IV—IV of Fig. 2. The cooling passages appear in this section as straight lines which cut the middle plane, for instance, at 28. The points at which these passages open into the inlet end surface of the strengthened middle part 6 are designated 29, and the points at which these passages come nearest to the cylinder axis are designated 34, which corresponds to the region of point A in Fig. 2.

Fig. 3 again shows the strengthened middle part 6 of the cylinder liner 1. The cooling passages are here arranged in a different manner. The middle part 6 is bored from the two sides 6', 6'', and two groups of passages 20, 24, 21, 25 are provided on each side, the axes of each group lying on a regular cone whose axis is the cylinder axis. Each pair of passages 20, 21 intersect in the middle plane of the cylinder. The passages 20, 21 are closed at 22, 23, so that the cooling medium flow follows the line C, D, E, F, G, the smallest distance of the passages from the cylinder axis presenting itself at D and F outside the middle plane E of the cylinder.

In order to come within the scope of the present invention, it is neither necessary that the passages be arranged symmetrically about the middle plane of the cylinder nor that the pairs of passages intersect on that middle plane. In the middle plane of the cylinder openings are provided for the fuel valves and possibly also for

the starting valves and other auxiliaries, but the passages may not be carried so far that they break into the openings in question, so that they are arranged so as to circumvent these.

In order to relieve the cylinder wall of circumferential stresses recesses 26, 27 (Fig. 5) may be provided on the inner side which run parallel to the passages in the middle part of the liner and thus relieve the hot zone of the wall, the recesses 26 reaching approximately to the cooled zone. The recess may also enter the wall more deeply still, as shown by recess 27.

I claim:

1. A cylinder liner for opposed piston internal combustion engines having a strengthened middle part surrounding the combustion chamber, a plurality of passages in the wall of said middle part oblique to the axis of the cylinder for the circulation of a cooling medium, the distance of said passages from the cylinder axis decreasing to minimum outside the middle transverse sectional plane of the cylinder.

2. A cylinder liner according to claim 1, in which the distance of the cooling passages from the cylinder axis is smallest in the zones in which the piston rings are situated when the pistons are at inner dead center.

3. A cylinder liner for opposed piston internal combustion engines having a strengthened middle part surrounding the combustion chamber, a plurality of passages in the wall of said middle part oblique to the cylinder axis for the circulation of a cooling medium, each of said passages having two distinct parts meeting at a vertex substantially in the middle transverse sectional plane of the cylinder, the two parts of each passage being so arranged that their respective distances from the cylinder axis decrease to a minimum in the zones in which the piston rings are situated when the pistons are at inner dead center.

4. A cylinder liner according to claim 3, in which the two parts of each passage are symmetrically arranged with respect to the middle transverse sectional plane of the cylinder.

5. A cylinder liner for opposed piston internal combustion engine having a strengthened middle part surrounding the combustion chamber, a plurality of passages in the wall of said middle part oblique to the cylinder axis for the circula-

tion of a cooling medium, each of said passages having two straight parts meeting at a vertex substantially in the middle transverse sectional plane of the cylinder, each group of passage parts lying on the same side of said plane being so arranged that the axes of the passage parts of each group belong to the generating lines of a single sided hyperboloid of revolution whose axis coincides with that of the cylinder.

10 6. A cylinder liner for opposed piston internal combustion engines having a strengthened middle part surrounding the combustion chamber, two rows of passages in the wall of said middle part for the circulation of a cooling medium, each of said passages having two distinct parts intersecting each other, the axis of every such part lying in a regular cone whose axis coincides with that of the cylinder, the vertices of intersection of the parts of one row of passages lying in the zone in which the piston rings of one of the pistons are situated when that piston is at inner dead center, the vertices of intersection of the parts of the other row of passages lying in a zone in which the piston rings of the other of the pistons are situated when that piston is at inner dead center, and corresponding parts of passages in one row intersecting corresponding parts of passages in the other row at vertices in substantially the middle transverse sectional plane of the cylinder.

30 7. A cylinder liner according to claim 1 in which recesses open to the combustion chamber are arranged in its middle part.

35 8. A cylinder liner according to claim 1 in which recesses open to the combustion are arranged in its middle part parallel to the cooling passages.

HANS STEINER.
